UNITED STATES PATENT OFFICE.

MILTON F. WILLIAMS, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

REDUCING SYSTEM.

1,116,777.

Specification of Letters Patent.

Patented Nov. 10, 1914.

Application filed May 9, 1914. Serial No. 837,448.

To all whom it may concern:

Be it known that I, MILTON F. WILLIAMS, a citizen of the United States, residing at the city of St. Louis, State of Missouri, have 5 invented a certain new and useful Improvement in Reducing Systems, of which the following is a full, clear and exact description, such as will enable others skilled in the art to which it appertains to make 10 and use the same, reference being had to the accompanying drawings, forming part of this specification, in which—

Figure 1 is an illustration of my improved reducing system. Fig. 2 is a section of the 15 form of grinder employed in my reducing system. Fig. 3 is an illustration of a modification of the system.

My invention relates broadly to milling, and specifically to a system of reducing light 20 materials, wherein is employed a grinder of special design.

In the reduction of light substances such as grain, wheat bran, screenings, middlings, shorts, ship-stuff and other by-products 25 commonly used as cattle feed, it is hard to get the reduced material through the grinding cage or concave of the grinder. This is due to the fact that the material being so light, it does not fall through the interstices 30 of the cage. Consequently, the efficiency of the mill is greatly reduced by the fact that the beaters are working in material which is already finely ground and which should have passed from the grinding chamber into 35 the discharge hopper.

My invention has for its particular object, the obviating of this difficulty, which is accomplished by forcing the reduced material through the cage by air pressure or suction. 40

Another object of my invention is to provide a reducing system which is absolutely dustless, all material which is discharged from the mill being handled in a closed system in which is provided means for separating the product and taking care of the dust. 45

My system obviates the necessity of discharging the dust into the air as well as the alternate necessity of employing some sort 50 of dust collector.

With the foregoing, and other objects, in view, all of which will be obvious or herein-after pointed out, it will be understood that my invention contemplates a specialized 55 form of mill having a grinding chamber 1,

a feed hopper 2, and a discharge hopper 4. A revoluble shaft 5 carries rotary beaters 6 which operate within the reducing chamber 1, coöperating with a breaker plate 7 and a foraminous cage 8. The foraminous cage 8 is interposed between the reducing chamber 1 and the discharge hopper 4, and one of its purposes in the mill is to determine the degree of fineness to which the material shall be reduced, as the material is retained to the action of the beaters until it is sufficiently fine to pass through the openings of the cage. 60

The feed hopper 2 communicates with the grinding chamber 1 through a feed opening 9. At one side of the feed hopper 2 is disposed an air inlet compartment 10, which communicates directly with the reducing chamber through an air inlet opening 11. Air is supplied to the air compartment 10 by the pipe 12. Communicating with the discharge hopper 4 is the discharge conduit 14 which leads to the eye of a centrifugal fan 15 carried on the machine and operated by the shaft 5. From the 70 discharge end of fan 15 a separator conduit 16 leads to a cyclone separator 17. This is a device well known in the art, which operates to break up the currents of air carrying the reduced material, permitting the material to be precipitated through the filling conduit 18 to any desired receptacle. Ordinarily there is considerable dust in the material which is not sufficiently heavy to be precipitated in the 75 separator, and this escapes with the air currents through a return conduit 19. This return conduit 19 communicates with the pipe 12 so that the air currents which leave the separator 17 are conducted to air compartment 10, carrying with them such light 80 dust as may be held in suspension. 85

It will be understood that the material to be reduced is fed to the mill from the hopper 2 through the feed opening 9. The 100 revolving beaters 6 first carry the material against the breaker plate 7 where it is crushed to a certain extent, and subsequently to the cage 8 where it is reduced by the co-operation of the beaters and the cage. Of course, in the reduction of the light materials enumerated, the material is carried around and around by the beaters and more or less of it will be in suspension in the 105 grinding chamber 1. Here it is that the 110

function of the air compartment 10 and the return of the air from the separator 17 thereto comes in. It is obvious that the action of the fan 15 is to create considerable pressure in the system made up of the pipes 16, 19 and 12, and the separator 17, and a considerable suction in the pipe 14 and discharge hopper 4. The result is that a considerable pressure of air is injected into the reducing chamber 1 from the air compartment 10, through the air inlet 11. This produces a considerable air pressure in the reducing chamber, which pressure finds its natural outlet through the foraminous cage 8 into the hopper 4, due to the reduced pressure in the hopper. The action of this air pressure finding relief from reducing chamber 1 into discharge hopper 4, has two important functions. In the first place, it forces the reduced material from the grinding chamber through the foraminous cage as soon as the material is sufficiently fine to pass through the openings. In the second place, it tends to hold the unreduced material on the cage 8 and prevent its being carried around and around by the beaters. It is obvious that when so held the material will be reduced much more rapidly than when it is carried about by the beaters.

A very important feature of the device lies in the fact that the injected air is introduced into the grinding chamber independently of the unground material so that the air does not influence the feed of the unground material into the mill. This prevents back pressure in the hopper 2, which back pressure would tend not only to hinder the entrance of the material into the grinding chamber, but also materially reduce the force of the injected current of air and thereby decrease its efficiency to force the ground material through the cage and hold the unground material on the cage.

The course taken by the air current is illustrated by the arrows in Fig. 2, and it will be seen that its course is almost diametrically across the orbit of the beaters. Therefore, the point at which the air is most efficient is on that part of the cage which is opposite the breaker plate. This is the part of the cage upon which is most of the finely reduced material. Therefore, it is obvious that the air currents are directed to where they can best be utilized in forcing the reduced material through the cage. Furthermore, it is at this point that the action of the air currents is most effective in preventing the reduced material being carried about by the beaters. When the dust which is introduced in the injected air is thus brought into contact with the newly reduced material, a considerable portion of the dust is caught and held by the heavier reduced particles, with the result that a considerable portion of the dust is precipitated

along with the particles which so carry it, when the material is introduced into the separator 17. Moreover, in view of the fact that the return currents from the separator are always conducted back to the mill, it is obvious that none of the dust will be permitted to escape into the open air.

Not only does this system render the operation dustless, and greatly increase the grinding efficiency of the mill, but it has a further valuable effect in keeping the mill cool, and in keeping the material cool. In case the material is of a sort which reduces slowly, or has a tendency to pack, thereby preventing a sufficiently rapid flow of the air from reducing chamber 1 into the discharge hopper 4, it is obvious that too great a pressure might be produced in the conduits 16 and 19 and in the separator 17. To prevent this, I employ a special form of relief, which consists of a fine mesh plaited bag 20 which is connected to the pipe 19 by a relief pipe 21. A cut-off 22 is provided in pipe 21 by means of which communication between the pipe 19 and the bag 20 may be opened or closed as occasions demand. The fine meshed bag 20 will permit a certain amount of the excess pressure in the system to exhaust therethrough, retaining the dust; such dust as collects in the bag 20 may be drawn off through a discharge valve 24 without being scattered in the air.

Illustrated in Fig. 3 is another form of relief consisting of the pipe 25 which leads from pipe 19 back to the discharge hopper or to pipe 14. This provides a by-pass through which excessive pressure may escape when conditions in grinding chamber 1 are such as to prevent its sufficiently rapid passage through the cage, and furnishes the proper air supply to the fan to enable the latter to keep the hopper clear of reduced material. By-pass pipe 25 is provided with a cut-off 26 by which the flow of air therethrough may be regulated. In the arrangement illustrated in Fig. 1, in case the passage of air through the cage is not sufficient to accommodate fan 15, outside air may be admitted to pipe 14 by means of a valve 27.

As illustrated in Figs. 1 and 2, a receptacle 13 may be placed in communication with pipe 12 adjacent its connection with the wall of the hopper. This receptacle is provided with a removable cap 13a. It often occurs that some metal or other refractory material becomes mixed with the material which is to be reduced, and is fed into the mill. When the rapidly revolving hammers strike this refractory material, it is thrown against the top of the grinding plate as shown in dotted lines Fig. 2, then back into the chamber 10 and into the pipe 12. The purpose of the receptacle 13 is to catch such material as may be ejected from the mill in this fashion as it slides back

down pipe 12. The removable cover 13^a permits the receptacle being cleared of such material as may be accumulated therein. The foreign material, which is usually in the form of metal or gravel, has sufficient momentum from the impact of the rapidly revolving hammers, to carry it against the current of air emitted from chamber 10. The material which is being reduced, however, being of a light nature, does not have sufficient momentum to make headway against the air current, and hence, such material is not thrown into chamber 10 or the receptacle 13.

15 From the foregoing, it is obvious that my improved reducing system provides a means for greatly increasing the efficiency of the grinder, for preventing wear of the mill by keeping it cool, for increasing the quality 20 of the product by preventing its heating, and for greatly improving the process by rendering it dustless.

I am aware that various changes and modifications may be made in the device 25 illustrated and described, without departing from the spirit of the invention or the scope of the appended claims.

What I claim is:

1. In a reducing system, the combination 30 of a separator, a grinder having a discharge hopper and a grinding chamber separated by a foraminous cage, said chamber being provided with a feed inlet and an air inlet, rotary beaters coöperating with said cage in said grinding chamber, means for reducing 35 the air pressure in said discharge hop-

per and increasing the air pressure in said separator whereby to inject air into said grinding chamber through said air inlet; said air inlet being disposed to direct a current of air across the orbit of said beaters to said cage.

2. In a reducing system, a mill comprising a grinding chamber and a discharge hopper separated by a foraminous cage, rotary beaters coöperating with said cage in said grinding chamber, a feed hopper and an air compartment having independent communication with said reducing chamber, means whereby air may be introduced under 40 pressure to said air compartment, and a receptacle communicating with said air compartment for the reception of material projected thereinto from the grinding chamber.

3. In a reducing system, a mill comprising a grinding chamber, revolute beaters operating therein, a feed hopper communicating therewith, an air compartment disposed adjacent the opening of said feed hopper, a conduit communicating with said air compartment and adapted to afford lodgment for material ejected from said grinding chamber into said air compartment, and means for forcing air into the air 50 compartment.

In testimony whereof I hereunto affix my signature in the presence of two witnesses, this 24th day of April, 1914.

MILTON F. WILLIAMS.
